Application May 27, 1942, Serial No. 444,642

7 Claims. (Cl. 77—5)

This invention relates to tools or the like and has particular reference to a new and improved tool having optical sighting means whereby the tool may be aligned with the work.

An object of the invention is to provide a new and improved device having optical sighting means for aligning the tool with the work and allowing use of the tool without the necessity of removing any of the optical members and without movement or possibility of injury thereto.

Another object of the invention is to provide a new and improved device having sighting means whereby a tool may be aligned with the work and which allows removal of the tool at any time for observing the effect of the tool on the work.

Another object of the invention is to provide a device adapted to support a tool relative to the work and having sighting means for positioning the tool relative to the work and said sighting means being so associated with the tool support that movement of the tool can be effected without any movement of the sighting means.

Other objects and advantages of the invention will be apparent from the following description taken in connection with the accompanying drawing and it will be understood that many changes may be made in the details of construction and arrangement of parts without departing from the spirit of the invention as expressed in the accompanying claims. We therefore do not wish to be limited to the exact details of construction and arrangement of parts shown and described as the preferred form has been shown by way of illustration only.

Referring to the drawing:

Fig. 1 is a sectional view taken through one form of apparatus embodying the invention; and

Fig. 2 is a sectional view taken through another form of apparatus embodying the invention.

Referring more particularly to the drawing wherein similar reference characters designate corresponding parts throughout the several views, the form of the device shown in Fig. 1 comprises an outer casing 1, an inner rotatable casing 2 rotatably mounted within said outer casing 1 and adapted to rotate within said outer casing 1 on the ball races 3.

The inner casing 2 is adapted to support a drill or the like at its lower end 4 and is also provided with a pulley or the like 5 adapted to receive a belt for rotation of said inner casing 2 although it will be understood that if desired said inner casing 2 may be so constructed as to be rotated by means of a suitable gear system.

Over the upper end of both the inner casing 2 and outer casing 1 is the cover member 6 to which is secured the sighting arrangement 7 and which also has the tube 8 extending within the inner casing 2 to a point adjacent the lower end of said casing 2. Said tube 8 contains the objective lens elements 9 which may be of desired form.

The sighting arrangement 7 comprises the eyepiece lenses 10 and the reticle 11 and right angle or reflecting sighting prism 12. This reticle 11 preferably has the target thereon in the form of concentric circles with a central cross hair. This sighting arrangement allows the operator to sight into the eyepiece 10 through the optical members in said members 7 and 8 and through the opening in the lower end of the inner casing 2, and align the center of the cross hairs on the target with the spot on which the tool is to be placed so that the drill or other tool is properly aligned with the work and then the drill or other tool is inserted in said opening 4 in the lower end of the casing and said casing 2 rotated by means of the belt or gear or other mechanisms described above to cause the tool to operate upon the work. If at any time it is desired to inspect the work it is only necessary to stop the rotation of the tool and remove the tool and inspect the work after which the tool can be replaced as described above for further operating upon the work.

It is pointed out that instead of employing the pulley or gear mechanism that an armature winding 18 may be positioned around the casing 2 for effecting rotation thereof.

It is particularly pointed out that with the present construction it is not necessary to remove any of the optical parts as has been necessary with prior constructions and also that the sighting arrangement 7 and lens tube 8 do not rotate during the drilling operation as they did with prior constructions, therefore eliminating any possibility of loosening or other damage to the optical elements.

In the modified form shown in Fig. 2 the apparatus has been considerably simplified. In this form only one casing 13 is employed and in this casing 13 is positioned the lens tube 14 which is aligned with the sighting device 15 and said casing 13 is adapted to be rotated on said lens tube 14 by the ball races 20.

Said casing 13 may be provided with the pulley 16 for rotation thereof or may be provided with suitable gear or other mechanism as described above.

55 The casing 13 is provided at its lower end with

a sighting opening 17 having suitable means for supporting the drill or other tool.

It will be seen that this form shown in Fig. 2 is a simplified form in that it eliminates one of the casings although possessing all of the advantages of the invention.

In operating the device shown in Fig. 2, which operates similar to the form shown in Fig. 1, the operator sights through the sighting arrangement 15 and lens tube 14 and opening 17 until the position for the tool is suitably aligned with the work and then the tool is placed in the holder 17 and the casing 13 is rotated by a pulley or gear mechanism to cause the drill or other tool to operate upon the work in a manner similar to that described for the form shown in Fig. 1 above.

While the apparatus has been described in connection with a drilling tool it will be understood that the use of said apparatus is not necessarily limited to use with a drilling tool but that the device may be employed in connection with other desired tools.

From the foregoing it will be seen that we have provided simple, efficient and economical means to obtain all of the objects and advantages of the invention.

Having described our invention we claim:

1. In a device of the character described, a rotatable tool support a sighting device having a portion thereof in telescoping relation with said tool support and aligned therewith and a portion not in telescoping relation with said tool support, said portions of said sighting device being in fixed optical aligned relation with each other, said tool support being capable of rotation with respect to said sighting device without movement of said sighting device and means for effecting rotation of said tool support.

2. In a device of the character described, a tool support having an opening adapted to receive a tool, a sighting device having a portion thereof in telescoping relation with said tool support and having a portion thereof in angular relation therewith and allowing the sighting through said opening adapted to receive a tool, said telescoping portion and said portion in angular relation being in fixed optical aligned relation with each other and a rotatable connection between said sighting device and said tool support whereby said tool support may be rotated with respect to said sighting device without any movement of said sighting device.

3. In a device of the character described, a tool support, a sighting device having a portion thereof in telescoping relation with said tool support and another portion in angular relation therewith, said telescoping portion and said portion in angular relation being in fixed optical aligned relation with each other, the portion of said sighting device in angular relation with said tool support including an eyepiece allowing the viewing of the work through an opening in said tool support, said tool support being adapted to support a tool for operation on said work.

4. In a device of the character described, a tool support, a sighting device having a portion thereof in telescoping relation with said tool support and another portion in angular relation therewith, said telescoping portion and said portion in angular relation being in fixed optical aligned relation with each other, the portion of said sighting device in angular relation with said tool support including an eyepiece allowing the viewing of the work through an opening in said tool support, said tool support being adapted to support a tool for operation on said work and said tool support being capable of rotation with respect to said sighting device without movement of said sighting device.

5. In a device of the character described, a hollow support having means for supporting a tool and a sighting arrangement for aligning said tool with the work, said sighting arrangement being in telescoping relation with said hollow support and having an optical system, said optical system being in aligned relation with said tool supporting portion of said hollow support and said tool supporting portion being rotatable relative to said sight, an eyepiece in fixed optical alignment with said optical system, said sighting arrangement being so supported relative to said hollow support that said hollow support may be rotated with respect to said sighting arrangement without any rotation of said sighting arrangement.

6. In a device of the character described, a hollow support having means for supporting a tool and a sighting arrangement for aligning said tool with the work, said sighting arrangement being in telescoping relation with said hollow support and having an optical system, said optical system being in aligned relation with said tool supporting portion of said hollow support, said hollow supporting portion being rotatable relative to said sight, an eyepiece optically aligned with said optical system and inclined relative thereto, said sighting arrangement being so supported relative to said hollow support that said hollow support may be rotated with respect to said sighting arrangement without any rotation of said sighting arrangement.

7. In a device of the character described, a hollow support having means for supporting a tool and a sighting arrangement for aligning said tool with the work, said sighting arrangement being in telescoping relation with said hollow support and having an optical system, said optical system being in fixed aligned relation with said tool supporting portion of said hollow support, said tool supporting portion being rotatable relative to said sighting arrangement, an eyepiece above and optically aligned with said optical system and in fixed inclined relation therewith, said sighting arrangement being so supported relative to said hollow support that said hollow support may be rotated with respect to said sighting arrangement without any rotation of said sighting arrangement.
